(57) **CLAIM**

The ornamental design for a retail display rack, as shown and described.

DESCRIPTION

FIG. 1 is a front, left perspective view of a retail display rack according to an embodiment;

FIG. 2 is a front, right perspective view of the retail display rack of FIG. 1;

FIG. 3 is a front elevation view of the retail display rack of FIG. 1;

FIG. 4 is a left side elevation view of the retail display rack of FIG. 1;

FIG. 5 is a right side elevation view of the retail display rack of FIG. 1;

FIG. 6 is a top plan view of the retail display rack of FIG. 1;

FIG. 7 is a bottom view of the retail display rack of FIG. 1; and,

FIG. 8 is a rear elevation view of the retail display rack of FIG. 1.

The broken lines are for illustrative purposes only and form no part of the claimed design.

1 Claim, 6 Drawing Sheets

Related U.S. Application Data

continuation of application No. 15/016,704, filed on Feb. 5, 2016, now Pat. No. 9,924,809.
